CURTAIN HANGER AND HOLD-DOWN

Annette E. Fridolph, New York, N. Y.

Application December 9, 1946, Serial No. 715,082

2 Claims. (Cl. 160—327)

1

This invention relates to a curtain hanger and hold-down and has to do particularly with an improved construction for slidably supporting a curtain, drape or other hanging in a manner to prevent a curtain from swaying objectionably or blowing about in the wind. In my application Serial No. 448,405 filed June 25, 1942, which has matured into Patent No. 2,412,608, granted Dec. 17, 1946, I have disclosed a unitary support for a hanging in which the usual traverse curtain rods are eliminated and the hanging is suspended from a small inconspicuous slotted track formed in the decorative surface of a window or door casing or other place where a hanging is to be slidably supported. This application is a continuation in part of the aforesaid application.

It is an object of the present invention to provide an improved construction of this type wherein a hanging may be not only suspended from the top but may be also anchored near its bottom to present a novel appearance and to prevent flowing in the wind.

Another object is to provide a hanging support of this nature wherein the curtain may be readily traversed from side to side and in which the top and bottom supports are carried along together without difficulty.

In many locations where drapes or curtains are to be hung, it is advantageous to secure them both at the top and at the bottom but previously used constructions have been difficult to manipulate when it is desired to open or close the curtain by sliding laterally. Thus, draperies which are hung directly on doors and in airplanes, automobiles, ships, railway cars, etc., where there are very strong air currents at times, require anchoring both at the top and at the bottom and, unless resort is had to rather elaborate traversing mechanism, they have been adjustable from side to side only with difficulty. Accordingly, the present invention aims to provide a simple rugged construction in which curtains of this type may be so hung as to be adequately anchored against blowing out in the wind and at the same time freely adjustable from side to side with great facility.

Figure 1 is a perspective view of a draped opening incorporating a preferred form of the present invention.

Figure 2 is a perspective view of a slider element used in Figure 1.

Figure 3 is a cross sectional view of a molding or casing strip used in Figure 1.

Figure 4 is a front view of part of the strip showing an aperture for inserting and removing the sliders.

Figure 5 is a perspective view of part of a slider tape unit used for the top of the assembly.

Figure 6 is a perspective view of part of a slider tape unit used for the bottom of the assembly.

Referring now to Figure 1, there is illustrated a two-part traverse drape 10 which is adapted for hanging in front of a cased opening 12 which may be a window, door or other panel requiring closure or decorative treatment. Formed in the upper casing member 14 is a track having a slot 16 of rather narrow width extending the full length of the opening. As shown more clearly in Figure 3, the slot is provided with an enlarged recess 18 behind the same. Such a track may be readily formed by slotting and routing out a wooden strip or casing member and may be small enough to be barely noticeable. A similar lower casing member 20 also has a track formed therein composed of an arrow slot 16 backed up by an enlarged recess 18.

At a convenient point near the end of each slot 16 there is formed an aperture 22 providing access to the recess 18 for the sliders by which the drapes 10 are suspended and to which they are anchored. These sliders are preferably formed as illustrated in Figure 2 where each comprises a flexible cloth tape 24 forming a band or strip having an enlarged head 26 which is also preferably cloth covered. The head 26 may be formed by taking a small channel shaped piece of non-corrosive metal 28 and completely wrapping it with the end portion of a piece of tape 24, after which the opposed edges of the channel are clamped together to firmly grip the tape. Thus the heads of the individual sliders are slender and rigid, while their connected cloth body portions or straps are flexible. These slider members may be individually stitched to each drape 10 at spaced intervals, or in a preferred construction 30 they are stitched to a running tape (30, 32 in Figs. 5 and 6) at the proper intervals, which tape is then sewed in proper lengths transversely to the back of each drape at top and bottom as indicated by dotted lines at 30 and 32, respectively, in Fig. 1.

The sliders at the top of the drapes are relatively short, their straps 24 being only sufficiently long to project through the slot to the point of attachment to the drape 10. The straps 24a at the bottom, however, are several times longer than those at the top and they are attached to the drapes 10 at a level considerably above the slot 16 in the lower member 20.

In operating, the slider members are permanently attached to the drapes 10 as indicated and the drapes may be hung from the casing members by inserting the slider members one at a time successively into the tracks through the apertures 22 at top and bottom and pulling so as to slide the drapes along as the sliders are in place. The rigid slender heads of gangs of individual sliders are received and held loosely in line within the recess 18 of each track member, 55 while their straps connected to the drapes ex-

tend freely through the slot 16. The heads of the sliders are unseated or removed through the apertures 22 by tilting and sliding movements, and this occurs almost automatically in removing them through angular pulls on their bands or the attached flexible hanging. When its sliders are inserted, each drape may be freely slid from side to side and will hang in natural folds determined to some extent by the spacing of the individual slider members. The long straps 24a at the bottom are flexible in all directions, and it has been found that the bottom slider members will follow along in the track as the drape is moved by shifting the top portion thereof. Thus, it is unnecessary forcibly to slide the bottom sliders in their track simultaneously with sliding the upper sliders.

At the same time, the drape hangs freely and its attachment at the bottom is not apparent when the drape is hanging in normal position. It is fully restrained, however, against swinging out into the room or out of the window if open, this restraint not interfering with the normal draped folds or with the normal traverse action. Hangers of this type are particularly useful in hanging curtains for the windows of vehicles or the doors of buildings and give the same appearance of curtains which are hung from the top only although, of course, they do not permit substantial displacement of the curtain from its normal position by air currents.

The drapes are, at the same time, readily put up and taken down and the slider members may remain permanently secured thereto. The heads may be made sufficiently small to withstand washing and passage through wringer rolls without damage, thus materially reducing the inconvenience in taking down and putting up drapes for laundering. At the same time, the cloth covering and slender form of the heads 26 makes them readily slideable in the track with perfect silence and very little friction while the universal flexibility of the straps 24 contributes materially to the natural hanging of the curtain in folds of pleasant appearance. The lengths of the head 26 of each slider member bears such relation to the length of the aperture 22 that the sliders will slide freely past the aperture when moved along the recess or groove 18.

In many cases the upper and lower casing members 14 and 20 of a window and the like are tapered, in other words, the distance between the members 14 and 20 might be closer at one end than at the other end, such as is the case in many automobile windows. In such an event the longer slider members, having straps 24a at the bottom, will compensate the varying distances between the upper and lower sections of a tapered window and will thus permit free sliding of the drapes back and forth.

It will be understood that the top and bottom members 14 may be positioned with their slotted

faces disposed either vertically as shown in Figure 3 or horizontally as shown in my copending application Serial No. 448,405. It also will be understood that one or a plurality of tracks may be used in each casing member, and in the latter case the respective members or drapes may slide past each other instead of just meeting.

I claim:

1. A flexible hanging, such as a curtain or drape for use on spaced upper and lower tracks bordering an opening, having a plurality of individual slider units secured at one end thereof to the top of said hanging at spaced points, another plurality of individual slider units secured at one end thereof adjacent the bottom of said hanging at spaced points, each of said slider units comprising a flexible band carrying at its other end a slider freely slideable on the corresponding track, the slider units at the bottom of said hanging having bands several times longer than the bands of the slider units at the top and being attached to the hanging at a level considerably above its lower edge, said hanging being normally free of tension between the upper and lower slider units to prevent said slider units from binding on said tracks.

2. A flexible hanging such as a curtain or drape for use in spaced upper and lower slotted tracks bordering an opening, having a plurality of individual slider units comprising thin straps secured at one end thereof to the top of said hanging at spaced points, another plurality of individual slider units comprising thin straps secured at one end thereof adjacent the bottom of said hanging at spaced points, and individual slender rigid heads carried by the other ends of and wider than the thickness of the respective straps for engagement with, and freely slideable in said slotted tracks, the slider units at the bottom having straps several times longer than the straps of the slider units at the top and being attached to the hanging at a level considerably above its lower edge, said slider units at the top of the hanging being secured to said hanging a sufficient distance from the slider units at the bottom of the hanging to allow the latter to hang freely from the upper track and to provide slack in the hanging between the upper and lower slider units, preventing binding of the slider units in said tracks.
